RADIO TUBE CLAMP

Percy Whittell, Philadelphia, Pa., and Frank J. Carraine, West Collingswood, N. J., assignors to Philco Radio and Television Corporation, Philadelphia, Pa., a corporation of Delaware

Application February 26, 1944, Serial No. 524,134

11 Claims. (Cl. 248—361)

This invention relates to radio tube clamping devices.

More particularly, the invention has reference to a clamping device designed to provide a means for securely holding radio tubes in their sockets, especially in radio installations subject to excessive vibration, such, for example, as in airplanes, tanks, and trucks. Without the use of some positive means to securely hold the tubes in such installations, the vibration tends to work the tubes out of their sockets and may at some crucial moment shut the operator off from needed radio communication.

Tube clamping devices have been used for such purpose, but a particular problem has arisen from the use of structurally different tubes adapted to the same socket. A tube having the stock number "6L6," for example, has a metal casing and an annular flange about its base, while the tube "6L6G" is an equivalent tube usable for the same purpose and in the same socket but having a glass shell with an unflanged plastic base. As far as known, until the development of the present invention there has been no single tube-clamp, acceptable to the industry, capable of positively clamping these two types of radio tube selectively in the same socket.

It is an important object of the invention, therefore, to provide a radio tube clamp designed to securely hold or clamp radio tubes of the aforesaid structurally different characteristics selectively in a single socket with which the said clamp is associated.

Another object is to provide a clamp of the aforesaid character that will permit easy and rapid replacement of the tubes in the associated socket irrespective of the said structurally different characteristics.

A further object is to provide a radio tube clamping device of simple design and inexpensive construction well adapted for mass production.

Other objects of the invention will appear from the following description considered in conjunction with the several views of the accompanying drawing, in which:

Fig. 1 is a fragmentary plan view showing a portion of a radio chassis embodying the invention;

Fig. 2 is a perspective view of the clamp removed from the chassis;

Fig. 3 is a sectional view, as on the line 3—3 Fig. 1, illustrating the manner in which the clamp functions to retain a glass tube in the socket;

Fig. 4 is a view similar to Fig. 3 but illustrating

the manner in which a metal tube may be held in the socket by the same clamp; and

Fig. 5 is a vertical sectional view showing the elements of the clamp in normal positions.

Referring to Fig. 1 of the drawing, the reference numeral 1 designates a fragmentary portion of a radio chassis having a tube receiving socket 2 provided with prong receiving apertures 3 and keyway 4, said keyway constituting a means for properly positioning the tube in the socket. This structure is in conformity with conventional practice and in itself forms no part of the present invention.

According to the invention, a substantially annular clamping device 5, preferably of relatively thin, hardened spring metal, embraces the socket 2. This device comprises flat horizontal base portions 7, 7 which, as shown, are located on the plane 1a of the top surface of chassis 1 and which are provided with apertures 7a through which screws 8 pass to anchor the device to the chassis at points circumferentially spaced about the axis 2a of the socket, and preferably at opposite sides of the socket as shown. Integral with base portions 7, 7 and forming opposite sides of the annulus are arcuate side members 9, 9 which normally diverge upwardly from the plane 1a at an angle preferably somewhat less than 45°. Each of the members 9, 9 has at its inner peripheral edge a bite portion 10, and at its outer edge an upwardly extending arm 11, said arm terminating in an outwardly flaring edge 12, upon which pressure may be conveniently applied to flex the side members 9, 9 toward the plane 1a of the chassis. Each of said arms 11 is provided with a pair of inwardly projecting ears 14, 14 the function of which will be hereinafter described.

It should be noted that bite portions 10, 10 are located normally in a plane 1b parallel with and spaced from plane 1a and that the flat inner edge of each of said bite portions occupies a plane perpendicular to the angularly disposed plane of its associated side member 9 and that the angular position of said member relative to the plane of the chassis causes a single sharp edge 10a of said inner edge to be presented relative to a plane perpendicular to said chassis, see Fig. 5.

In practice and as illustrated in Fig. 3, the clamp is normally in the position illustrated by broken lines 5a. When a glass tube 16, such as the previously mentioned "6L6G," is to be inserted in the socket 2, the tube is pressed downwardly between the arcuate side members 9, 9 of the clamp, flexing these members outwardly and downwardly about their lines of juncture with the base por-

tions 7, 7 to an extent permitting the prongs of the plastic base 17 of the tube to enter the proper apertures 3 in the socket as determined by the keyway 4 in accordance with conventional practice. When the tube is fully "home" in the socket, as illustrated, the sharp inner edges 10a engage the side surfaces of the base 17 by virtue of the resiliency of said members and thereby create an effective interlock between the clamp and said base. As shown in Fig. 1, the arcuate shape of the inner edges of the bite portions 10 are such that base 17 is gripped throughout the length of said edges, and while this is preferred it will be apparent that the desired interlock may be effected by other edge formations.

When the base 17 has been gripped by the edges 10a, vibration of the chassis acts to tighten the grip since the edges tend to bite into and interlock with the base and thereby positively prevent the tube from working out of the socket. To remove the tube from the socket, however, it is only necessary to exert pressure against the outwardly flaring edges or pressure surfaces 12 of the arms 11 to flex the arcuate members 9, 9 outwardly and to thereby break the engagement of bite edges 10a with the base of tube which may then be withdrawn from the socket.

If it is desired to replace the glass tube with a metal tube 20, such as aforesaid "6L6," see Fig. 4, the tube is pressed downwardly against arcuate side portions 9, 9 as described above until they have flexed outwardly far enough for the base 21 of tube to pass therebetween. This metal tube has an annular flange 22 about its base which, during said downward movement, engages first the flaring top edges 12 of the arms 11 and then engages the inclined edges 15a of the ears 14 and by camming action with said edges flexes the portions 9, 9 to an extent permitting said flange to pass to a position below the ears, the said portions 9 then springing upwardly and inwardly to an extent engaging the bottom edges 15 of the ears over the flange and thereby locking the tube in the socket 2. This tube may be removed in a manner similar to that described in connection with glass tube 16.

It can be seen that the ears 14 also act to reinforce the arms 11, rendering them substantially rigid and preventing them from flexing when pressure is applied upon the surfaces 12, 12. Downward pressure upon said surfaces is thus translated into immediate flexure of the said members 9, 9 toward the plane of the chassis. Rigidity of the arms 11 is desirable also in connection with the metal tube 20 to prevent the arms from flexing outwardly under pressure exerted by the tube in a direction away from the socket. By reason of said rigidity such pressures can tend only to draw the side members toward each other around the base members 7, 7 as a fulcrum and thus to tighten the hold of the clamp on tube.

It should be understood that the bite portions 10 may be eliminated and the inner edges of side members 9, 9 be designed to engage the base of tube 16 either frictionally or in a manner similar to the gripping edges 10a to prevent accidental displacement of the tube from the socket. Also, the side members 9, 9 may be made as separate pieces each having base portions 7, 7, such portions being secured at a common point as illustrated or at separated points. Furthermore, while the arcuate shape of these members is preferable, they may assume other convenient shapes. While one of the side members 9 is sufficient to

hold the tube in its socket in some instances, two are generally more effective and are desirable. The clamping device has been described in connection with a glass envelope plastic base tube and a flanged base metal envelope tube, but it should be understood that these tubes have been used for illustrative purposes only, and the invention is not to be construed as limited to tubes of this particular construction since clamps employing the principle of the invention may be used to advantage with other types of cylindrical and flange based tubes.

A desirable feature of the invention resides in the fact that the clamp may be manufactured by simple stamping and bending methods which lend themselves well to mass production.

It will be understood that the clamping device herein described and illustrated is subject to substantial modification without departing from the scope or spirit of the invention as defined in the appended claims.

We claim:

1. A tube clamping device consisting of a substantially annular member having opposite arcuate resilient side portions diverging angularly from one side of a common base plane and with respect to each other for embracing the base of said tube, each of said side portions having an inwardly directed bite portion for clamping engagement with said base, and having an arm extending away from said plane and beyond the said bite portion, and an inwardly projecting shoulder-forming lug on said arm also for clamping engagement with said base.

2. A tube clamping device consisting of a substantially annular member having opposite arcuate resilient side portions diverging angularly from one side of a common base plane and with respect to each other for embracing the base of said tube, each of said side portions having an inwardly directed bite portion for clamping engagement with said base and having an arm extending away from said plane and beyond the said bite portion and terminating in an outwardly flared extremity, and an inwardly projecting shoulder-forming lug on said arm also for clamping engagement with said base.

3. A tube clamping device consisting of a substantially annular member having opposite arcuate resilient side portions diverging angularly from one side of a common base plane and with respect to each other, each of said side portions having an inwardly directed bite portion, and having an arm extending away from said plane and beyond the said bite portion and terminating in an outwardly flared extremity, and an inwardly projecting shoulder-forming lug on said arm having an inner surface inclined inwardly toward said plane.

4. A tube clamping device consisting of a substantially annular member having opposite arcuate resilient side portions diverging angularly from one side of a common base plane and with respect to each other, each of said side portions having an inwardly directed shoulder-forming lug the inwardly facing surface of which is inclined inwardly toward said plane, and said side portions having each an inwardly directed bite portion in position intermediate the lug and said plane.

5. A tube clamping device consisting of a substantially annular member having opposite arcuate resilient side portions diverging angularly from one side of a common base plane and with respect to each other, each of said side portions

having an inwardly directed shoulder-forming lug and having an inwardly directed bite portion in position intermediate the lug and said plane, said bite portion comprising a short inward projection from said resilient side portion having an arcuate edge.

6. A tube clamping device comprising resilient substantially flat arcuate members oppositely arranged in embracing relation with the base of said tube, said members diverging angularly from one side of a common base plane and with respect to each other, the inner edge of said members forming an inwardly directed bite portion for clamping engagement with said base, an arm projecting from the outer edge of each of said members and away from said plane, and an inturned shoulder-forming ear on each of said arms also for clamping engagement with said base.

7. In combination, a radio tube socket adapted to selectively receive tubes having structurally different characteristics, a tube clamp adapted to releasably maintain said tubes in said socket, said clamp comprising base portions secured respectively at apposite sides of said socket, and arcuate resilient side members having inner and outer edges and diverging upwardly from said base portions to form with the latter a substantially ring-like structure surrounding said socket, each of said side members having at its inner edge and intermediate its ends an inwardly directed bite portion adapted to grip the base of a cylindrical-base tube, and each of said side members having on its outer edge and intermediate its ends an inwardly projecting element adapted to overlie a flange of a flanged-base tube.

8. In a radio chassis, a tube socket, and means associated with said socket to securely hold a tube in said socket, said means comprising a substantially ring-like device surrounding said socket and having oppositely arranged base portions secured to said chassis respectively at opposite sides of said socket, and spring metal side members diverging angularly from said base portions, said members having inwardly directed edges adapted to grip said tube and oppose movement thereof from said socket, and extended arms terminating in outwardly flared edges to provide a pressure surface for flexing said side members toward the chassis to sever engagement of said gripping edges with the tube, said arms having inwardly turned reinforcing ears to reinforce said arms and to render them substantially rigid, said ears being operative also to overlie the flange of a flanged-base tube to hold it in said socket and being releasable from said flange by flexure of 55 said members toward the chassis.

9. In a radio chassis, a tube socket, and means associated with said socket for securely holding a tube in said socket, said means comprising a pair of resilient side members diverging angularly from said chassis and from each other and partially surrounding said socket, means for anchoring said members to the chassis, each of said members having a tube gripping edge arranged to grip the peripheral base of a tubular-base tube by virtue of the resilient bias of said members to thereby hold the tube in said socket, said members being flexible toward the chassis in response to pressure thereon to disengage said grip, each of said members also having an extending arm 15 with inwardly projecting ear portions arranged to overlie an outwardly extending flange on a flanged-base tube to hold said tube in the socket, said ears being releasable from said flange by flexure of said members toward the chassis.
10. A device for securing a radio tube in its socket, said device comprising a pair of complementary sheet spring-metal members arranged to at least partially encircle the base of a radio tube installed in said socket, means for anchoring 20 said members in position adjacent to the tube socket with each said member extending from its point of anchorage away from said anchorage and angularly with respect to the tube axis, each of said members having a base-gripping edge and 25 said edges being oppositely disposed with relation to the tube base and being operative conjointly to grip the peripheral surface of the said base by virtue of the resilient bias of said members, each of said members being flexible in response to 30 pressure to a position wherein the said gripping edge is disengaged from the tube base, said members each having an ear-like appendage disposed remotely from the point of anchorage of its respective member and operative to overlie an outwardly projecting flange on a flange-based tube, 35 said appendage being releasable from said flange by flexure of said members.
11. A construction in accordance with claim 9 wherein said ear-like appendages are substantially 40 triangular with a horizontal base edge adapted to overlie said tube flange and inner edges inclined outwardly from said base edge and constituting camming surfaces for engagement with the tube base when the tube is inserted in the 45 socket whereby the said base may act to flex the members outwardly.
